Nashua, N. H.

Application August 9, 1937, Serial No. 158,084

24 Claims. (Cl. 93—61)

The principal object of my invention is to provide a machine which will apply adhesive, such as glue, over a predetermined area, less than the entire area, of a transparent window then cut through the glue as the window is cut from the web of window material and then apply the window, while the glue is moist, to the opening in the envelope blank. One advantage is that the glue may be applied to the very edge of the transparent window so that there will be no danger of the window being unglued at its edge. If the window is not glued at its very edge it may project slightly from the envelope and be torn away from the envelope and this is especially true as to that edge of the window which faces the letter or other thing when the latter is inserted in the envelope. Whether the glue is applied so as to extend to all four edges or to any number of edges less than four may be controlled by an appropriate gum applicator.

Before my invention the envelope industry had sought for years to apply glue so that the windows would adhere at their edges but this was never successfully done because the adhesive was applied to the envelope blank and slight variation in register would cause the adhesive to offset with relation to the combining mechanism with consequent jamming of, and otherwise interfering with, the practical operation of the machine.

My use of predetermined glued area of the transparent windows permits the use of the cheapest glassine equally as well as the more expensive acetate, especially because of the relatively small area which is glued whereas, in the prior art, the use of previously coated and dried window materials sealed to the envelope blank with heat or moisture necessarily limits the types and kinds of window material and increases cost because of the expense of the window material.

Another feature of my invention is the feeding and conveying of the die-cut aperture envelope blanks. Such blanks cannot be drawn one over another as they tend to lock and tear through and interfere one with another. Such interference is completely done away with by my invention which provides that each blank is individually gripped and rolled away from the pile or stack, the grippers maintaining positive control, and register of the individual blanks up to, and past, the window-applying mechanism and until the very instant that they are discharged individually for further operations.

Satisfactory adhesive for window envelopes should be heavy and tacky. One of the most

serious difficulties encountered in prior machines is the tendency of the glue pad to pull the envelope blank away from its conveying mechanism. This tendency is much greater on the thin and delicate transparent window material and my invention represents an important advance in the art in the manner in which I prevent the window material from being drawn out of register by the glue applicator, this being done in the form shown by means of suction.

Another feature of my invention is means to cut through the moist glued web of window material combined with means to carry the moist severed windows and register them with the envelope blanks.

Another feature of my invention is that the glue wheel travels at an extremely slow speed so that no air is churned up into the glue. Attempts have been made to move the glue roll intermittently to avoid this objection, but these have not been successful as the glue roll applicator must travel at the same speed as the envelope blank. With my invention however the glue applicator travels merely the length of the window blank, which is only a small fraction of the space required for each envelope.

Another feature of my invention is that the location of the transparent window can be varied with respect to the envelope blank, both longitudinally and laterally, and this also while the machine is in operation.

Another feature of my invention is the means for cleaning the cutting mechanism so that glue will not accumulate.

Still another feature of my invention is moving the envelope blank against the stationary window blank, the latter having moist glue thereon, and preferably this movement of the envelope blank is a rolling movement.

Other features will be pointed out below.

In the drawings:

Fig. 1 is a front elevation of the machine;

Fig. 2 is a right side elevation of the machine;

Fig. 3 is a plan of the envelope blank;

Fig. 4 is a plan of the window blank;

Fig. 4a is a plan view of a modified form of window blank;

Fig. 4b is a perspective view of a preferred form of glue-applying roll;

Fig. 5 is a plan view of the envelope blank having the window applied thereto;

Fig. 6 is a vertical cross sectional view through the machine on the line 6—6 of Fig. 1;

Fig. 6a is a sectional detail of the knife cleaning mechanism.

- Fig. 7 is a detail vertical cross sectional view on the line 7—7 of Fig. 1;
- Fig. 8 is a vertical cross sectional view through the machine on line 8—8 of Fig. 1, enlarged;
- 5 Fig. 9 is a detail vertical cross sectional view through a portion of the machine on the line 9—9 of Fig. 1, enlarged;
- Fig. 10 is a plan view of the upper portion of the machine;
- 10 Fig. 10a is a detail view of a portion of the mechanism for adjusting the window feeding and positioning mechanism;
- Fig. 11 is a detail vertical cross sectional view on line 11—11 of Fig. 8;
- 15 Fig. 12 is a detail vertical cross sectional view on line 12—12 of Fig. 10;
- Fig. 13 is a detail vertical cross sectional view on line 13—13 of Fig. 10;
- 20 Fig. 14 is a perspective of the roll unit and carrying chains;
- Fig. 15 is a detail rear elevation of the take-off roll mechanism partially broken away.
- The main drive shaft 1 is provided with a pinion 2 on the outside of the right side frame 25 member 19, that is connected to a sprocket shaft gear 3 through idler 4. The sprocket shaft gear 3 is mounted on a sprocket shaft 5 that carries two sprockets 6 inside and adjacent to the side frames 19. Sprocket shaft gear 3 is connected 30 to an upper sprocket drive gear 7 through an idler 8. The upper sprocket drive gear 7 is fixed on a shaft 9 that also carries two sprocket wheels 10 aligned with sprockets 6. Connecting the two sprocket wheels 10 with the two sprockets 6 are 35 chains 11, one on each side of the machine inside and adjacent to the frames 19. Rotatably mounted in the chain 11 are a plurality of shafts 12 each carrying intermediate of its ends a roll 13 that has at its ends heads 14. On the outer 40 extremities of the shafts 12 are gears 15 that engage toothed tracks 16, each of which is composed of two semi-circular internal gears 17 and two sections of straight racks 18. The entire toothed tracks 16 are secured to the inside of the 45 frame members 19. Rotation of the shaft 1 transmits rotation to shafts 5 and 9 carrying sprockets 6 and 10 connected by chains 11 upon which are mounted rolls 13 causing them to move in the direction of the arrow of Fig. 8 and also to rotate counterclockwise about their shafts 12, as 50 they pass around the track 16.
- Pivottally supported on shafts 9 are brackets 20 on the outside and adjacent to the frames 19. These brackets 20 carry a shaft 21 rotatably mounted therein and having gears 22 meshing with segments 23 secured to the tracks 16. Said shaft 21 also has worm gear 24 secured to it at its left hand end, as viewed in Fig. 1, meshing with worm 25, that is mounted on left hand bracket 60 20 and which is operated by hand nut 26. Rotation of the hand nut 26 transmits rotary motion to shaft 21 causing gears 22 and shaft 21 to ride around segment 23 about the shaft 9. Shaft 21 carries brackets 20 also about the shaft 9 for 65 adjustment purposes and threaded bolts 27 clamp brackets 20 to the frames 19 in the desired position.
- Side frames 28 and 29 are pivottally mounted upon the shaft 21 just inside the brackets 20 and adjusting screws 30 allow an adjustment between the side frames 28 and 29 and the brackets 20 about the shaft 21. The brackets 20 carrying shaft 21 and the parts mounted on shaft 21 are therefore adjustable, as a unit, about the shaft 75 9 and the side frames 28 and 29 with the parts they support are adjustable, as a unit, about the shaft 21. These adjustments permit positioning of the six-sided suction roll 64 in any desired location upon the path of rolls 13.
- Inner side frames 32 and 32a are pivottally 5 mounted on shaft 21 and are connected to tie rod 33, which also connects side frames 28 and 29, (see Fig. 10). Side frames 32, 32a and the mechanism between therefore move as a unit with side frames 28 and 29. A shaft 31 is supported by side frame 10 28 and inner frame 32 and is connected by gears 34 and pinion 35, which is on fixed shaft 31, to the gear 7. The outer end of shaft 31 carries an arm 36 and roll 37 which, in cooperation with a Geneva wheel 38 upon shaft 39 constitute an intermittent power transmission mechanism (see Fig. 5). Shaft 39 is supported by side frame 28 and inner side frames 32 and 32a. The resultant motion of shaft 39 is such that upon one revolution of the shaft 31 it causes one-sixth of a revolution of the shaft 39.
- Upon the shaft 31 is a gear 40 adjacent the inside of the inner side frame 32 (see Fig. 10). Said gear 40 meshes with a pinion 41 on the shaft 42 which carries the upper feed roll 43 for the web 25 of transparent paper 44 (see Fig. 12).
- A gear 45 upon shaft 42 meshes with and drives pinion 46 fixed on shaft 47. Also secured on shaft 47 is the lower feed roll 48 for the web of transparent paper. Feed rolls 43 and 48 pull 30 the transparent web 44 over two idler rolls 50 from transparent web roll 49 supported between inner side frames 32 and 32a. Shaft 47 of lower feed roll is rotatably mounted in two side arms 51 that rest upon tie bars 52 (Fig. 12). The remote end of the arm 51 from the shaft 47 is spring pressed downwardly by spring 53 and the arm rests on the forward tie bar 52 causing the shaft 47 and its feed roll 48 to be spring pressed upwardly against the upper feed roll 43. A cam handle 54 is provided for releasing this pressure while the web is being threaded through the feed rolls.
- A pinion 55 upon the shaft 42 drives a gear 56 fixed on the same shaft as the cement feeding 45 roll 57. A doctor roll 58 driven by the gear 56 is also provided for regulating the amount of glue on the glue-feeding roll. The lower portion of glue-feeding roll 57 runs in a glue supply box 59 picking up the glue at its lower portion and carrying it past the doctor roll 58 and thence to the glue applying roll 60. The glue applying roll 60 is carried on shaft 61, said shaft 61 being driven by gear 45 meshing with pinion 62 on glue-applying roll shaft 61.
- The glue-applying roll 60 is provided with two cut-out portions so that no glue is applied to the web over a predetermined area which is slightly larger than the opening of the envelope blank shown in Fig. 3, Fig. 4, showing the extent of the glue indicated at 63, the purpose being to prevent the glue from reaching the cut-out portion of the envelope. All of the above mentioned feeding rolls and glue-applying mechanism are rotated continuously while blanks are 65 in position to be operated on, all being driven from the shaft 31, said rolls and mechanism stopping when there is no blank present.
- In Fig. 4b I show a form 60a of glue-applying roll mounted on shaft 61a similar to shaft 61. 70 This roll applies glue to only two margins of the window element.
- The shaft 39 has a six-sided suction roll 64 secured to it. Said suction roll 64 has twelve longitudinal bores 65 running throughout its en-

tire length. These are connected to the periphery of the roll 64 by openings 66 arranged in two rows on each face of the roll 64. A collar 67 slidably adjustable upon the shaft 39 and provided with pistons 68 one in each bore 65 is used for blocking off as many of the holes 66 as desired, depending upon the width of the transparent paper web 44 (see Fig. 10). On the opposite end of the roll 64 a valve 65 is provided so that contact by suction is provided between the web 44 and the upper forward and lower surfaces of the roll, as viewed from the front of the machine. This suction therefore holds the web 44 of transparent paper upon the roll 64 until it has been glued to the envelope blank 70. A portion of the valve 71 is spring pressed towards the valve member 65 by spring 72 and is geared directly to continuously rotating shaft 42 by means of gearing 73. Valve member 65 is held stationary by a bracket to the cross bar 78, while roll 64 is rotated intermittently.

It has heretofore been stated that the feeding rolls 43 and 48 are rotated continuously to advance the web 44 of transparent material to the suction roll 64. It has also been pointed out that the shaft 39, upon which the suction roll 64 is fixedly secured, is intermittently rotated by the Geneva wheel 38 which is secured to the shaft 39 and actuated by the arm 36 and roll 37 of the shaft 31. The continuous rotation of the feeding rolls 48 and 42 during the time that the suction roll 64 is at rest will advance the web of transparent material sufficiently to form a slack loop as illustrated in Fig. 8. When however the suction roll 64 is actuated by the Geneva mechanism it is rotated at a sufficiently higher rate of speed than the speed at which the web is continuously advanced by the feed rolls 48 and 42 to take up the slack and draw the web tightly upon the peripheral face of the cylinder so that when suction is applied through the opening 66 the section of the web which engages the periphery of the cylinder will be held smoothly and tightly thereupon by suction. Suction is maintained upon portions of the web thus caused to adhere to the periphery of the cylinder as the cylinder is rotated to cutting position in which the section is severed therefrom and the section is still maintained in contact with the periphery of the suction cylinder until the section forming the window is applied to the envelope blank as illustrated in Fig. 8.

Roll 64 has at the apex of its sides slots 75 through which pass the slot-cutting knife 76 when the roll 64 is not rotating. Knife 76 is fastened to chain 77, which is mounted over sprockets 78 on cross bar 79 between the two inner brackets 32 and 32a. Roll 79a is rotatably mounted in a water box 79b mounted on cross bar 79 and cooperates with a roll 79c which is held downwardly by a spring 79d. The knife 76 passes between the rolls 79a and 79c, the lower of which runs in a water bath in box 79b to clean the knife 76 as it passes between said rolls. A pair of bevel gears 80, one of which is fixed on shaft 81, drive the chain 77. The shaft 81 is driven from the continuously operating shaft 31 by means of gears 82. The knife 76 enters into the slot 75 and traverses the entire length of said slot to effect cutting of the transparent paper web 44 in order to cut up the continuous web into sections of suitable size to cover the opening in the envelope blank 70. The edge of the suction roll 64 and the adjacent reach of the chain 77 are at a slight angle to effect a shearing cut of the

knife 76 on the web 44. A cam 83 on shaft 81, in cooperation with a roll 84 mounted on a bell crank lever 85, locks the shaft 39 in six successive positions when the shaft 39 is not being driven through its intermittent driving mechanism. 5

By reason of the construction above described it will be obvious that the web of transparent paper or window material is maintained in contact with the periphery of the vacuum cylinder by 10 vacuum alone from the time the web of material is drawn taut upon the upper surface of the cylinder until a section thereof is brought into registry with the traveling blank to which it is to be applied and that this adhesion of the transparent material to the suction roll is maintained during the severance therefrom of the sections which are to be applied to the successive traveling blanks. 15

In the construction illustrated a plurality of 20 sections have been severed from the web at the time the foremost is applied to the traveling blank, or in other words the continued rotation of the suction roll carries the severed section and also carries a previously severed section into contact with the traveling blank. 25

A stack of envelope blanks 70 rest on two rods 87 which are adjustable crosswise of the machine by means of threaded screw 88. Rods 87 are carried by bars 89 which are adjustable vertically by means of adjusting screws 90. Rods 87 and bars 89 are clamped to a cross rail 91 by set screw 92, said cross rail 92 being rigidly mounted between the side frames 19 of the machine. Fingers 93 support the extreme ends of the envelope 35 blank 70 and fingers 94, which are mounted on bars 95, align the top portions of the blanks 70. Bars 95 are also adjustable on the cross rail 91. The lower corner of the blank 70 rests on adjustable plates 96, the lower of which is cut out at 40 its innermost end to allow a blank-releasing finger 97 to pass through. Two spring pressed supporting members 98 also hold the innermost blank 70 of the stack near its lowermost point. Blank-releasing finger 97 is slidably mounted on 45 key 99 and resiliently mounted to bell crank arm 100 by pin 101 and spring 102.

The innermost end of bell crank arm 100 is held upwardly by spring 103, the upper end of which is fastened to cross rail 91. The bell crank 50 arm 100 is pivoted on cam lever 104, said cam lever 104 carrying a roll 105 that engages a cam 106 on main drive shaft 1. This cam lever 104 is pivoted on rod 107 and actuated upwardly and downwardly by cam 106 to effect the releasing 55 of the lowermost corner of the blank 70 at the desired time. Pivotedly mounted on rod 107 is a second cam lever 108 that carries a roll 109 which, in conjunction with cam 110 on shaft 1, effects an upward and downward motion of the cam lever 60 108 about the rod 107. On the end of cam lever 108 is pivotally mounted a bell crank arm 111 carrying a roll 112 actuated by a cam 113. The operation of cam 113 causes a rotation of the bell crank arm 111 about its pivot on cam roll 65 arm 108. The cam roll 112 rotates idly about a pin 114 fastened in the bell crank arm 111 and in a bracket 115, which is also secured to pin 114. Bracket 115 carries a suction tube 116 which extends upwardly to a point adjacent the lowermost corner of the blank 70. The combined motion transmitted by cams 110 to cam roll 108 and cam 113 to bell crank arm 111 effect a movement to the suction tube 116, causing it to raise up behind the lowermost corner of the inner blank 70 75

and contact the same, then receding away from the stack of blanks to a position where this end of the blank 70 may be picked up by blank-carrying means upon rolls 13. Then the suction tube 116 is moved downwardly and out of the path of the rolls 13.

A bracket 106a secured to the cross rail 91 carries a lever 106b, one end of which contacts a cam bump 106c and the other end of which carries a hammer 106d, a spring 106e being provided to hold the hammer 106d normally against the cross rail 91. The cam bump 106c on the hub of the cam 106, upon passing one end of the lever 106b, allows the spring 106e to pull the hammer 106d against the cross rail 91 and effect a vibration in the stack of blanks 70 to facilitate the operation of the suction tube 116 and the blank-engaging fingers 97. A valve 116a on shaft 1 controls the interval when the suction is applied within the tube 116, that is, when it engages the end of the blank 70 until the time the jaws 123 engage the end of the blank.

The fingers 97 are moved downwardly at the time the suction tube is applied to the end of the blank 70 freeing the same. Mounted in the heads 14 of the roll 13 is a shaft 120, which is provided on its right hand end with a dog 121 and inside of the roll 13 carries two fingers 122. Loosely mounted on rod 120 are two envelope blank engaging jaws 123. Between the fingers 122 and jaws 123 is a spring 124, which normally holds the envelope blank-engaging fingers against the outer surface of the roll 13. A trip dog 125 is rigidly mounted to the inside of the right frame 35 of the machine to contact the dog 121 and effect an opening of the blank jaws 123 at the proper time and place, that is, when they come adjacent to the end of the innermost blank as it is held by the suction tube 116. As the roll 13 passes 40 this point, the dog 121 is returned to its normal position by a spring 126 closing the blank-engaging jaws 123 on the lower portion of the blank 70. Further movement upwardly of the roll 13 rolls the blank up on it. As it is rolled past the 45 roll 64 holding the cut-up web with the glued side downwardly, the suction is taken off the lowermost section of the web and the envelope is allowed to contact this section gluing the two together. Further movement of the roll 13 in its 50 orbit carries it around to a point adjacent a pick-off roll 130 provided with a rubber nozzle 131.

Roll 130 is mounted on shaft 132, said shaft being driven from the gear 7 by gears 133 and 134. A valve 135 is mounted on a sleeve 163 secured in the frame 19 by screw 137 and suction is provided by this valve at the proper time to effect a pick-up of the blank 70 by the nozzle 131 as they contact. A releasing dog 140 controlled by a cam 141 on conveyor shaft 142 strikes the dog 121 at the time the blank is contacted by the nozzle 131 to effect a releasing of the blank from the roll. Conveyor shaft 142 is driven from gear 8 by means of gear 143. Sprockets such as 144 on conveyor shaft 142 carry chains such as 145 65 to convey the completed blank to a folding machine.

As the blanks 70 are rolled up on the drums 13 and as the drums 13 move in an upwardly direction, they pass a contact wiper of a usual type. 70 If a blank is on the drum 13 no electrical contact is made between the drum and the contact member, but if no blank is on the machine a connection is made whereby the relay 151 is energized causing the lever 152 to be pulled down at 75 its end adjacent the relay. The hook end of the

lever 152 then becomes engaged from a pin 153 mounted on clutch lever 154, causing clutch lever 154 to drop and disconnect the outside end of shaft 31 from the inside end through one-revolution clutch 155. A cam 156 actuates a reset lever 157 secured to pin 158, to which clutch lever 154 is also secured. This interruption of motion between the inner and outer ends of the shaft 31 prohibits the feeding of the web 44 when no blank 70 is being carried by the drum 13. A switch 160 operated by a cam 161 is in series with the contact member to also effect breaking the electric circuit through the relay 151.

In general, the operation consists of picking up a blank 70 by a roll 13 and rolling it past a section of the web 44 that has a predetermined area of moist glue upon it, then conducting the roll 13 to a take-off roll 130 which deposits the assembly of the blank and the portion of the web on a conveyor 145, the cut-off portion of the web being applied to the web while the glue is moist.

As the chain 11 is rotated clockwise, as viewed in Fig. 8, it carries one of the rolls 13 to a point adjacent the lower tip of the blank 70. At this point the dog 121 on the shaft 120 carried by the drum 13 engages the trip dog 125, causing the jaws 123 to open. The suction tube 116 engages the lower tip of the innermost blank 70 and pulls it into a position where the jaws 123 of the drum 13 will engage it and clamp it to said drum 13. The rotative movement of the drums 13, as they go counterclockwise and upwardly, as viewed in Fig. 8, causes the blank 70 clamped by the jaws 123 to be rolled up on the drum 13. The web 44 is fed at a predetermined rate by the web-feeding rolls 43 and 48 past a glue-applying roll 60, that applies moist glue over a predetermined area. The web is then fed on to a six-sided roll 64, each face of which is concaved to the path taken by the peripheries of the rolls 13 as they pass around shaft 9 as their axis. A knife 76 cooperates with slots 75 in roll 64 to cut up the web 44 in sections to be applied to the envelope blanks 70. The rolls 13, as they roll by the suction roll 64, pick up the web section so that they are superimposed over the cut-out portions of the blank 70. Continued movement of the rolls 13 cause the dogs 121 to be engaged by a cam operated trip dog 140 to effect the releasing of the end of the blank by the jaws 123 and allow the nozzle 131 on the drum 130 to pick up the blank 70 and deposit it upon the conveyor 145.

By reason of the present invention therefore I have produced a novel method of applying transparent windows to an apertured envelope blank which consists essentially in applying adhesive to predetermined marginal areas of a web of transparent window material, then cutting the web of transparent material through the adhesive so that the adhesive completely covers the edge portions of the window and cause it unfailingly to adhere to a portion of the blank which surrounds the aperture of the envelope, and then applying the window when thus severed from the strip to the envelope while the adhesive is still moist.

The method further comprises applying to a strip of transparent material predetermined areas of adhesive at intervals corresponding to the marginal portions of adjacent windows, cutting the strip through the adhesive, positioning the window, then presenting an apertured window envelope to the positioned window in such manner that the window will be transferred from the positioning means and applied to the envelope 7

over the aperture thereof, and finally removing the envelope from the position in which the window is applied to it.

It will be understood that the particular embodiment of the invention shown and described herein is of an illustrative character and that various changes in construction of the machine and in the method of applying to apertured envelopes windows having the marginal portion thereof coated with a moist adhesive may be made within the spirit and scope of the following claims.

Having thus described the invention, what is claimed as new, and desired to be secured by Letters Patent, is:

1. The method of applying a transparent window to an apertured envelope blank consisting in applying wet adhesive to predetermined narrow areas of a web of transparent material through which the cutting of the window blank from the web takes place, then cutting through the web and adhesive while the latter is moist to sever the window from the web in such manner that the moist adhesive extends to the edge of the window and then applying the severed window while the adhesive is moist around the aperture in the envelope blank thereby causing the window to be glued along its very edge to the envelope blank.
2. The method of applying a transparent window to an apertured envelope blank consisting in feeding a window with moist adhesive thereon to a position of rest, feeding a portion of the envelope blank adjacent to said aperture into engagement with the portion of the stationary window having moist adhesive thereon to cause adhesion between the window and blank and then feeding the window and blank, adhering together, away from said position of rest.
3. The method of applying a transparent window to an apertured envelope blank consisting in feeding a window with moist adhesive thereon into a concave position of rest, rolling a portion of the envelope blank adjacent to said aperture into convex engagement with the portion of the stationary window having moist adhesive thereon to cause adhesion between the window and blank, and then feeding the window and blank, adhering together, away from said position of rest.
4. A machine for applying transparent windows to apertured envelope blanks comprising means to apply moist adhesive to predetermined areas of portions of a web of transparent material through which the cutting of the window from the blank takes place, each of said areas being a peripheral part only of the entire area of each window to be cut from said web, means to cut through the web and the moist adhesive area, thereby to sever each window from the web, an endless carrier having means for successively feeding said envelope blanks to cause registry of the window apertures therein with the severed window, and means to cause the adhesive-coated peripheral edge area of each window to engage the envelope blank adjacent to the aperture in said blank while the adhesive is still moist, thereby insuring adhesion of the peripheral edge of the window to the envelope blank.

5. A machine for applying transparent windows to apertured envelope blanks comprising means for supporting a stack of envelope blanks, means to feed a web of transparent material, means for applying moist adhesive to predetermined areas thereof through which the cutting of the window from the blank is to take place,

means for cutting through said web and moist adhesive to form a window having moist adhesive extending to its edge throughout its periphery, means to feed the window having adhesive thereon into position to engage an envelope blank, and means to engage positively an envelope blank and carry it from the stack into adhesive engagement with said window and to carry the blank and window adhering together away from said position.

6. A machine for applying transparent windows to apertured envelope blanks comprising means for supporting a stack of envelope blanks, means to feed a window having adhesive thereon into position to engage an envelope blank, means to engage positively an envelope blank and to carry it from said stack into adhesive engagement with said window and to carry the blank and window, adhering together, away from said position, and means to free the blank and adhering window from said engaging means.

7. A machine for applying transparent windows to apertured envelope blanks comprising means for supporting a stack of envelope blanks, means to feed a window having adhesive thereon into a stationary position in concave form to engage an envelope blank, a roll, means carried by the roll to engage positively an envelope blank and carry it from said stack in convex form around said roll into adhesive engagement with said window and to carry the blank and window, adhering together, away from said position.

8. In a machine of the character described a set of juxtaposed feeding and adhesive applying rolls acting continuously to feed and to apply adhesive to predetermined narrow areas of a web of transparent window material, means to receive material from said applying means, and receiver actuating means to control the registry of said material on said receiving means with relation to said feeding means as said material leaves said applying means.

9. In a machine of the character described a set of juxtaposed feeding and adhesive applying rolls acting continuously to feed and to apply adhesive to predetermined narrow areas of a web of transparent window material, rotatable means to receive said material from said applying means, and suction means carried by said receiver and receiver actuating means to control the registry of said material on said receiver with relation to said feeding means as said material leaves said applying means.

10. In a machine of the character described the combination of means to apply adhesive to a web of transparent window material, means to feed said web away from said applying means including a rotary member having a plurality of concave portions on its periphery, means to rotate said rotary member intermittently, suction means to hold said web in concave form in said concave portions, means to sever a window from said web, said suction acting to hold said window in position after such severance, means to feed an envelope blank in convex form into adhesive engagement with said severed window, and means to render the suction on said severed window inactive after said adhesion has taken place.

11. In a machine of the character described the combination of means to feed a web of transparent material having moist adhesive areas transversely thereof, a cutter, means for moving said cutter longitudinally of said web to cut a window section from said web at the portion of the latter where there is moist adhesive, and

- means to wash said cutter after each severance of a window section from said web.
12. In a machine of the character described the combination of means to feed an envelope blank into position for adhesive engagement with a window, means to feed said window, carrying adhesive, into position for adhesive engagement with said blank, and means for varying the location of said window with relation to said blank for said adhesive engagement, such variation being longitudinally as well as laterally of the machine.
13. In a machine of the character described the combination of means to feed an envelope blank into position for adhesive engagement with a window, means to feed said window, carrying adhesive, into position for adhesive engagement with said blank, and means for varying the location of said window with relation to said blank for said adhesive engagement, such variation being longitudinally as well as laterally of the machine, said varying means being operative whether the machine is operating or not.
14. A machine for applying transparent windows to apertured envelope blanks comprising means for feeding a strip of transparent material, means for successively applying adhesive to predetermined areas of said strip corresponding to marginal areas of adjacent windows, an intermittently rotatable window-positioning member having pneumatically operable means to engage a window area of said strip having the moist adhesive applied thereto, a cutter, means for moving the same lengthwise of said positioning means to sever a window from said strip through the adhesive-coated area while attached to said positioning member, and means for successively presenting apertured envelope blanks in registry with said window-applying means to cause the window to be applied over the aperture thereof.
15. A machine for applying transparent windows to apertured envelope blanks comprising means for feeding a strip of transparent material, means for successively applying adhesive to predetermined areas of said strip corresponding to marginal areas of adjacent windows, an intermittently rotatable window-positioning member having pneumatically operable means to engage the window area of said strip having the moist adhesive applied thereto, and provided with longitudinal slots corresponding to the width of the window, means for severing a window pane from said strip lengthwise through the adhesive-coated area while attached to said positioning member comprising an endless chain having a cutting blade, and means for intermittently actuating said chain to cause said blade to pass successively through said slots, and means for successively presenting the apertured envelopes to said window-applying means to cause the window to be applied over the aperture thereof.
16. A machine for applying transparent windows to apertured envelope blanks comprising means for supporting a stack of envelope blanks, a traveling carrier having means to engage and successively move said blanks from the stack and present them to a window feeding and positioning means comprising intermittently operable means for feeding a strip of transparent material, means for successively applying adhesive to predetermined areas of said strip corresponding to marginal areas of adjacent windows, an intermittently rotatable window-positioning member having means to receive the window area defined by the moist adhesive, means for severing a window from said strip lengthwise of the adhesive-coated portion thereof while on said positioning means, and means for applying a window to said blank over the aperture thereof.
17. A machine for applying transparent windows to apertured envelope blanks comprising means for supporting a stack of envelope blanks, a traveling endless carrier provided with a series of rotatable rolls having means to engage and successively remove said blanks from the stack and present the same to a window-feeding and positioning means, comprising a rotatable member having means to receive and hold a window having a moist adhesive upon the marginal area thereof, and means for actuating said rotatable member and said rolls in proper correlation to apply the window to the envelope blank accurately over the aperture thereof.
18. A machine of the class described, means for positively and continuously feeding a web of transparent material, means for applying adhesive to predetermined transverse areas of said web during the continuous movement of said web, a rotary drum having suction means to engage the web of transparent material delivered from said feeding means, means for intermittently rotating said drum, means for cutting said web of material while on said drum comprising a knife cooperating with said drum and means for moving said knife lengthwise of said drum in coordination with the intermittent movements of said drum to sever predetermined lengths of said transparent material from said web through the adhesive coated areas thereof, and means for applying said severed lengths of transparent material successively to suitable blanks.
19. A machine of the class described, means for positively and continuously feeding a web of transparent material, means for applying adhesive to predetermined areas of said web during the continuous movement of said web, a rotary drum having suction means to engage the web of transparent material delivered from said feeding means, means for cutting said web of material while on said drum comprising means for actuating said cutting means in coordination with the rotation of said drum to sever predetermined lengths of said transparent material from said web, means for feeding blanks in cooperative relation to the severed areas of transparent material carried by said drum, and means for adhesively securing together said transparent areas and said blanks in predetermined relation.
20. A machine of the class described, means for adhesively uniting two sheets of material on predetermined areas, comprising a continuously moving blank carrier, a cooperating suction roll having a plurality of rows of vacuum holes, means for continuously feeding a web of transparent material to said suction roll, means for rotating said suction roll at a greater peripheral speed than the speed at which the web is fed to said suction roll, means operable successively to sever sections of transparent material from the web, and means for causing the suction to hold the end portion of the web of transparent material in contact with the drum and also to hold a previously severed section against the drum during the progressive application thereof to a traveling blank.
21. A machine of the class described, means for adhesively uniting two sheets of material on predetermined areas, comprising a continuously moving blank carrier, a cooperating suction roll having a plurality of rows of vacuum holes, means

for continuously feeding a web of transparent material to said suction roll, means for rotating said suction roll at a greater peripheral speed than the speed at which the web is fed to said suction roll, cutting means cooperating with said suction roll successively to sever sections of transparent material from said web, said vacuum serving unaided to hold the transparent material upon said cylinder until it registers properly with the traveling blank.

22. A machine of the class described, means for adhesively uniting two sheets of material on predetermined areas, comprising a continuously moving blank carrier, a cooperating suction roll having a plurality of rows of vacuum holes, means for continuously feeding a web of transparent material to said suction roll, means for rotating said suction roll at a greater peripheral speed than the speed at which the web is fed to said suction roll, cutting means cooperating with said suction roll successively to sever sections of transparent material from said web, said vacuum serving unaided to hold the transparent material upon said cylinder and prevent disturbance thereof by the action of the cooperating cutter and thereafter to carry the severed section into proper registering position with the traveling blank.

23. A machine of the class described, means for adhesively uniting two sheets of material on predetermined areas, comprising a continuously moving blank carrier, a cooperating suction roll having a plurality of rows of vacuum holes, means for continuously feeding a web of transparent material to said suction roll, means for

rotating said suction roll at a greater peripheral speed than the speed at which the web is fed to said suction roll, cutting means cooperating with said suction roll successively to sever sections of transparent material from said web, said suction operable to retain a plurality of said severed sections on said suction roll, and means for progressively releasing the severed sections therefrom as the sections are joined progressively with a continuously moving blank.

24. A machine of the class described, means for adhesively uniting two sheets of material on predetermined areas, comprising a continuously moving blank carrier, a cooperating suction roll having a plurality of rows of vacuum holes, means for continuously feeding a web of transparent material to said suction roll, means for rotating said suction roll at a greater peripheral speed than the speed at which the web is fed to said suction roll, means for severing sections of transparent material from said web including a cutter movable relatively to the periphery of said drum, complementary means in the periphery of the drum, means for actuating said cutting means in coordination with the rotation of said suction roll and the continuously operable blank-feeding means to cause the severance of sections of predetermined length from the web and means controlling said suction to cause the adherence of the severed section to the suction roll until such section is brought into registry with the traveling blank.

LEWIS C. PEARCE.
